UNITED STATES PATENT OFFICE

PHILLIP H. KAUFMAN, OF CLEVELAND HEIGHTS, OHIO

BOOK WITH PAGE-RULING ATTACHMENT THEREFOR

Application filed December 14, 1927. Serial No. 239,880.

This invention relates to notebooks, and has for its general object to provide articles of this character with devices whereby lines may be readily ruled upon either or both 5 sides of the sheets thereof and at varying distances apart and from the margins of such leaves. Further and more limited objects of the invention will appear hereinafter and will be realized by the construction and 10 arrangement of parts shown in the drawings hereof, wherein Fig. 1 represents a perspective view of a notebook having my invention applied thereto; Fig. 2 a transverse sectional view through such notebook, showing 15 the same in its open position and with one of my ruling devices in operative relation to one of the leaves; and Fig. 3 a detail in perspective showing a modification.

Describing the various parts by reference 20 characters and in connection with Figs. 1 and 2, A represents the body of the notebook, the same consisting of a plurality of leaves which may be secured at their middles to the backing, the said backing being 25 shown as continuous and comprising a front cover B and a back cover B'. The leaves are shown as provided with the lines A² running parallel with the top and bottom thereof.

In order to enable the leaves to be ruled 30 with lines running across the lines A² and preferably at right angles thereto, line rulers, indicated generally at C and C', are carried by the edges of the covers B and B' which are adjacent to the free edges of the leaves A. 35 Each of these line rulers is made conveniently of cardboard having wide slots C² and C³ respectively therein, these slots extending longitudinally of their respective rulers—that is at right angles to the direction of the 40 lines A². These slots are separated by solid portions C⁴ and C⁵, respectively, which solid portions and slots are of such width as to enable spaced lines to be drawn upon the leaves A by using the opposite edges of the 45 sides of each slot for straight edges. The width of the slots and of the solid portions is shown herein to be such as to enable equally-spaced lines to be ruled on the leaves. A further advantage in employing the wide 50 slots is that they give visibility to the lines

while being drawn, as the operator can see clearly both the starting and finishing point of any line which he wishes to draw. Furthermore, they accommodate drawing instruments of considerable width and also enable material and data to be lined up within their confines as, for instance, columns of figures.

Each of the line-rulers C and C' is connected to an edge of the front and back 60 covers of the book respectively and form foldable extensions of such covers, the attachment being shown as made at the side edges of such covers and being conveniently obtained by using strips D, D' of flexible 65 material, each pasted or otherwise suitably secured at one edge to such edge of the front and back covers, respectively, and each having its opposite edge pasted or otherwise suitably secured to an edge of the rulers C 70 and C', respectively. This flexible connection is of sufficient width in each case to enable the entire stack of leaves bound within the book to be received beneath each of the rulers C, C', and still enable such ruler to lie 75 flat upon the top of the stack. The strips D, D' may be made of tough and pliable paper, or cloth, or any other flexible material suitable for the purpose.

In Fig. 3 there is shown a modification of 80 my invention wherein a line ruler C⁶ is shown as formed integral with the cover B' to which it is secured or attached, the flexibility of this integral connection between the ruler and the back being secured by scoring or inwardly creasing the outer surface of the connecting portion C', the scores or creases being indicated at C⁸.

With the parts constructed and arranged as described, it is believed that the operation of 90 my invention in connection with a notebook will be readily understood. When it is desired to rule upon a leaf of the book lines such as shown at E, extending across the lines A² on such leaf, by folding one of rulers upon the appropriate leaf, the lines may be drawn 95 quickly, conveniently and accurately upon the appropriate side of such leaf by means of a pencil or other instrument F, as indicated in Fig. 2. To draw lines upon the opposite side 100

of the same leaf or upon the sides of other leaves which face the cover which carries the ruler just used, the other line ruler will be employed, as shown in Fig. 1, being folded over upon the sides of the leaves which face away from the cover to which such ruler is applied.

By the conjoint action of the two line rulers C and C', the opposite sides of the leaves of a notebook may be quickly and conveniently ruled; and, when the line rulers are not in use, they may be folded inwardly against their respective covers, as shown in connection with the ruler C in Fig. 1 and the ruler C' in Fig. 2.

While I have shown the line rulers as attached to the side edges of the front and back covers, it is obvious that they may be attached to the tops or bottoms of said covers, if desired.

Having thus described my invention, what I claim is:

1. A book having foldable front and back covers and a series of leaves interposed therebetween, said book comprising also a slotted line-ruler having an edge connected to the outer edge of its front cover and a slotted line ruler having an edge connected to the outer edge of its back cover, the said line rulers being foldable onto opposite sides of the leaves interposed between said covers, thereby enabling the ruling of lines on opposite sides of the said leaves.

2. A book comprising foldable front and back covers and a series of leaves interposed therebetween, said book comprising also a line-ruler for each cover, and a flexible connection between an edge of each such ruler and the outer edge of the cover with which it is associated, said connections including means whereby the said rulers may be folded on opposite sides of the leaves interposed between said covers and of such width as to accommodate between each ruler and the cover to which it is attached a variable number of leaves while the ruler lies flat on top of the particular leaf which is to be ruled thereby.

3. A stack of leaves having a foldable cover, and a slotted line ruler having an edge connected to an outer edge of said cover, the said line ruler being foldable onto the said leaves, thereby enabling the ruling of lines on one side of each of said leaves.

4. A book comprising a stack of leaves and a foldable cover therefor, and a slotted line-ruler carried by an outer edge of said cover and foldable from said cover on top of and away from such stack, the said ruler being provided with ruling slots therein of such width as to enable opposite sides of each slot to be used as straight edges for drawing spaced lines.

5. A book comprising a stack of leaves and a foldable cover therefor, and a slotted line-ruler for said leaves, the said ruler constituting an integral continuation of an outer edge

of said cover and said connection being made flexible at its junction with the said cover whereby the said ruler may be folded on top of one or more of the leaves in said stack while enabling the ruler to lie flat on top of such leaves notwithstanding variations in thickness of the stack therebeneath.

6. A book having foldable front and back covers and a series of leaves interposed therebetween, said book comprising also a slotted line-ruler having an edge connected to the outer edge of its front cover and a slotted line-ruler having an edge connected to the outer edge of its back cover, the said line rulers being foldable onto opposite sides of the leaves interposed between said covers, thereby enabling the ruling of lines on opposite sides of the said leaves, said slotted line-rulers being provided with parallel slots having parallel edges, the width of said slots being substantially equal to the distance between them.

In testimony whereof, I hereunto affix my signature.

PHILLIP H. KAUFMAN.
